(57) **CLAIM**

The ornamental design for clamp, as shown and described.

DESCRIPTION

FIG. 1 is a perspective view of a clamp showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view thereof showing the clamp in another position when it is engaged; and,

FIG. 9 is perspective view thereof shown in use.

The broken lines in the drawings represent unclaimed environment only and form no part of claimed design.
